[57] CLAIM

The ornamental design for a fishing rod and reel, as shown.

DESCRIPTION

FIG. 1 is a perspective view of a fishing rod and reel showing my new design;

FIG. 2 is a right view thereof;

FIG. 3 is a left view thereof;

FIG. 4 is a top view thereof;

FIG. 5 is a bottom view thereof;

FIG. 6 is a front view thereof; and,

FIG. 7 is a rear view thereof.

The fishing rod is shown broken away for clarity of illustration to indicate indeterminate length.
